TAKE-UP AND LET-OFF RELEASE
MECHANISM

Walter J. Budzyna, East Douglas, Mass., and
William E. Lundgren, New Britain, Conn., as-
signors to Draper Corporation, Hopedale, Mass.,
a corporation of Maine

Application January 29, 1941, Serial No. 376,498

6 Claims. (Cl. 139—99)

This invention pertains to looms and more particularly relates to let-off and take-up mechanisms therefor.

In certain types of looms the let-off and take-up mechanisms are operated from some moving part of the loom, usually the lay sword. Accordingly whenever it becomes necessary to turn the loom by hand, as when a pick-out occurs, it is necessary that the let-off mechanism and the take-up mechanism be rendered inoperative.

Various devices for rendering the let-off mechanism and the take-up mechanism inoperative have been proposed. However, such prior devices have either been too complicated and expensive to manufacture or have been inconvenient to operate.

Accordingly it is a principal object of the present invention to provide in a loom of the type aforesaid having a let-off mechanism including a member movable from operative to inoperative position, reciprocating means engaging the member when in operative position for actuating the let-off, and take-up mechanism including a ratchet and pawls, a simple, inexpensive and convenient means for rendering said mechanisms inoperative, which shall comprise a single manually operable lever pivotally mounted on the loom and means connecting said lever to said member and to one of said pawls and arranged to render said mechanisms inoperative when said lever is depressed.

This and other objects of the invention are accomplished in the construction illustrated on the accompanying drawings, wherein:

Fig. 1 is a side elevation of the left hand side of a loom showing the let-off and take-up mechanisms together with our invention applied thereto.

Fig. 2 is a front view of part of the mechanism shown on Fig. 1;

Fig. 3 is a plan view of one detail of the mechanism for disconnecting the let-off mechanism;

Fig. 4 is a side view of the mechanism shown on Fig. 3; and,

Fig. 5 is a side view partly in cross section of the mechanism for disconnecting the take-up mechanism.

The drawings show a well known form of loom having my invention applied thereto. The drawings show a left hand loom side frame 1, a lay sword 2, a warp beam 3, let-off mechanism indicated generally at 4 and take-up mechanism indicated generally at 5.

The particular type of let-off mechanism shown is a "positive" type of let-off and may be similar

to the well known Bartlett type of let-off. The let-off mechanism may comprise a bracket 6 mounted on the side frame 1. A vertical shaft 7 having a hand wheel 8 at one end and a ratchet wheel 9 at the other is mounted in bearings carried by the bracket. A worm 10 is fixed to shaft 7 intermediate the ends thereof. A horizontal shaft 11 is geared to the warp beam at one end and has a worm wheel 12 geared to worm 10 at the other end. A pawl carrier 13 having two pawls 14 and 15 for engaging the ratchet wheel 9 is loosely mounted on vertical shaft 7. A rod 16 is pivotally connected to pawl carrier 13 at one end and is slidably mounted in a bearing 17 at the other end. A reciprocating lever 18 is adjustably connected to the sword as at 19 and has an upturned apertured end 20 which slidably engages the rod 16. The lever 18 engages a member 21 pivotally attached to a bracket 22 mounted on rod 16 for moving rod 16 to the right, as viewed on Fig. 1, to thereby rotate the ratchet wheel 9 and shaft 7 in a direction to effect let-off of the warp sheet from the warp beam. A coiled spring 23 is mounted on rod 16 between bracket 22 and bearing 17 for moving rod 16 to the left, as viewed on Fig. 1.

Member 21 has a concave bottom surface adapted to embrace rod 16. At its rear end member 21 is convexed as at 24 so that upon engagement with the concave surface 25 of the upturned end 20 of lever 18, the member 21 will not be pushed upwardly. The forward end of member 21 is bifurcated, forming arms 26 and 27. A pin 28 extends through a projection 29 formed on the bracket 22 and arms 26 and 27 are pivotally mounted on pin 28. A set screw 30 extends through the projection 29 and engages the pin 28 to hold the pin in position. Member 21 has a lug 31 extending laterally therefrom for a purpose hereinafter to be described.

When the pivoted member 21 is in its lowered position embracing rod 16 it is in operative position and upon operation of the loom, member 21 will be engaged by the upturned end 20 of reciprocating lever 18 to effect operation of the let-off mechanism. When member 21 is raised to inoperative position out of engagement with rod 16, member 21 will not be in position to be engaged by the upturned end 20 of lever 18 and the let-off mechanism is rendered inoperative.

The take-up mechanism may be of the usual ratchet and pawl type and may comprise a horizontal shaft 32 mounted in bearing 33 on the left hand side frame 1 and bearing 34 on an upright 35. Shaft 32 has a hand wheel 36 fixed thereto

on one end, a ratchet wheel 37 fixed thereto adjacent the hand wheel and a gear 38 adjacent the other end for driving the gear train (not completely shown) of the take-up mechanism. A pawl carrier 39 is loosely mounted on shaft 32. Pawl carrier 39 has a driving pawl 40 pivotally mounted thereon and an arm 41 extending downwardly therefrom. A reciprocating rod 42 is adjustably connected to the arm 41 as at 43 and is adjustably connected to the sword as at 44.

A stub shaft 45 is mounted in a bearing 46 on a bracket 47 fixed to the left hand side frame 1. A hold back pawl 48 is fixedly connected to one end of shaft 45. A spring, not shown, is provided for urging the hold back pawl 48 downwardly into contact with the ratchet wheel 37. An arm 49 is fixedly connected to the other end of shaft 45 by means of set screw 50. Arm 49 has an opening 51 therein, for a purpose hereinafter to be described.

When the hold back pawl 48 is in engagement with the ratchet wheel 37 it is in operative position and upon operation of the loom, reciprocating rod 42 will rotate the ratchet wheel 37 and shaft 32 in a direction to effect operation of the take-up mechanism. When the hold back pawl 48 is raised to inoperative position out of engagement with the ratchet wheel 37, the take-up mechanism is rendered inoperative as the reciprocation of lever 42 will only cause the ratchet wheel to oscillate.

The mechanism for rendering the let-off and take-up mechanisms inoperative may comprise a manually operable lever 52 fixedly attached to one end of a stub shaft 53 by means of set screw 54. Stub shaft 53 is rotatably mounted in a bearing 55 carried by a bracket 56 attached to the front girt 57. A collar 58 is fixedly mounted on shaft 53. A coiled spring 59 is mounted on shaft 53 between bearing 55 and collar 58 and has one end 60 attached to collar 58 and the other end 61 attached to the bearing 55. A stop 62 is carried by bracket 56. Coiled spring 59 tends to turn the shaft 53 counter clockwise, as seen on Fig. 2 thereby bringing the upper surface 63 of lever 52 into contact with the stop 62 and holding the lever 52 in a horizontal position. A Bowden wire 64 has a head 65 on one end clamped in a boss 66 on bracket 56 by means of set screw 67. The head 65 of the Bowden wire has a plunger 68 normally projecting therefrom into engagement with the outer end 69 of lever 52. The other end of the Bowden wire 64 has a head 70 clamped in a boss 71 formed on the bracket 22 by means of set screw 72. The head 70 of the Bowden wire has a plunger 73 projecting therefrom and engaging the lug 31, as best seen on Fig. 4. The construction is such that when the inner end 74 of lever 52 is pressed downwardly, the outer end is raised pushing the plunger 68 into the head 65 causing the plunger 73 to be further projected from head 70 thereby raising the lug 31 and moving member 21 to inoperative position, thus rendering the let-off mechanism inoperative.

A rod 75 has one end 76 extending through the opening 51 in arm 49 and the other end 77 extending through an opening 18 in the outer end 69 of the lever 52. An adjustable collar 79 is fixed to rod 75 directly below arm 49 and an adjustable collar 80 is fixed to rod 75 directly above the outer end 69 of the lever 52. The construction is such that when the inner end 74 of lever 52 is depressed, the outer end 69 engages the collar 80 and raises the rod 75 which by means

of collar 79 raises the arm 49 and thereby moves the hold back pawl 48 to inoperative position out of engagement with the ratchet wheel 37.

The operation of the device is as follows:

When for any reason a pick-out is necessary, the loom is stopped and then turned over by hand for the necessary number of picks to make the pick-out.

When the loom is turned over by hand for a pick-out it is highly desirable that the let-off and take-up mechanisms be rendered inoperative. With our invention this is easily accomplished by the loom operator.

After the loom has stopped and before turning it over by hand the operator steps upon the inner end 74 of lever 52. This causes the Bowden wire to raise the member 21 to inoperative position so that when the loom is turned over by hand the lever 18 will not move rod 16 and operate the let-off. At the same time the rod 75 is raised thereby lifting the hold back pawl 48 to inoperative position. With the hold back pawl 48 inoperative, when the loom is turned over by hand the drive pawl 40 will merely oscillate the ratchet wheel 37 and will not rotate the take-up, so the take-up is rendered inoperative. When the operator removes his foot from the lever the let-off and take-up mechanisms are again rendered operative.

It should be noted that the particular type of let-off and take-up mechanism shown is by way of illustration only as our invention is equally adaptable to other types of let-offs and take-ups.

Having thus fully disclosed the preferred embodiments of our invention, we claim:

1. In a loom having a let-off mechanism including a member adapted to be moved from an operative to an inoperative position and reciprocating means engaging said member and actuating said let-off mechanism only when said member is in operative position and a take-up mechanism including a ratchet and pawls with means connected to one of said pawls for moving same to an inoperative position to thereby render said take-up mechanism inoperative, the combination of a single manually operable lever pivotally mounted on said loom, a member having one end associated with said lever and the other end associated with said first named member for moving the latter to inoperative position when said lever is depressed and a member connecting said lever and said second named means for actuating the latter to move said pawl to inoperative position when said lever is depressed whereby upon depressing said lever said let-off mechanism and said take-up mechanism simultaneously are rendered inoperative.

2. In a loom having a let-off mechanism including a member adapted to be moved from operative to inoperative position and reciprocating means engaging said member only when said member is in operative position for actuating said let-off and a take-up mechanism including a ratchet and pawls with one of said pawls being adapted to be moved from operative position to an inoperative position to thereby render said take-up mechanism inoperative, the combination of a manually operable lever pivotally mounted on the loom, a Bowden wire having one end associated with said lever and the other end associated with said member for moving said member to inoperative position when said lever is depressed and means connecting said lever and said pawl for moving said pawl to inoperative position when said lever is depressed, whereby upon de-

pressing said lever said let-off mechanism and said take-up mechanism simultaneously are rendered inoperative.

3. In a loom having a let-off mechanism including a member movable from operative to inoperative position and a reciprocating means engaging said member when said member is in operative position for actuating said let-off and a take-up mechanism including a ratchet wheel, driving pawl, and a stub shaft mounted on the loom and having a hold back pawl fixedly mounted on one end thereof for engaging the ratchet wheel with said hold back pawl being adapted to be moved from engagement with said ratchet wheel to an inoperative position to thereby render said take-up mechanism inoperative, the combination of an arm fixedly attached to the other end of said stub shaft, a manually operable lever pivotally attached to the loom, a push rod having one end connected to said lever and the other end connected to said arm for moving said hold back pawl to inoperative position when said lever is depressed and a member having one end associated with said first named member and the other end associated with said lever for moving said first named member to inoperative position when said lever is depressed, whereby said let-off and said take-up mechanisms simultaneously are rendered inoperative upon depressing said lever.

4. In a loom having a let-off mechanism including a stop member movable from operative to inoperative position and reciprocating means engaging said member only when said member is in operative position for actuating said let-off and a take-up mechanism including a ratchet wheel, a driving pawl and a stub shaft having a hold back pawl fixedly attached to one end with said hold back pawl being adapted to be moved from operative to inoperative position to thereby render said take-up mechanism inoperative, the combination of an arm fixedly attached to the other end of said shaft, a manually operated lever pivotally attached to the loom, a push rod having one end connected to said lever and the other end connected to said arm for raising said arm to thereby move said hold back pawl to inoperative position when said lever is depressed and a Bowden wire having one end associated with said stop member and the other end associated with said lever for moving said stop member to in-

operative position when said lever is depressed whereby said let-off and said take-up mechanisms are rendered inoperative upon depressing said lever.

5. In a loom, a let-off mechanism including a shaft, a ratchet wheel fixed thereto, a pawl carrier loosely mounted on said shaft and having a pawl engaging said ratchet wheel, a rod pivotally connected to said pawl carrier at one end and 10 slidably mounted in a bearing on the loom at the other end, a stop member pivotally connected to said rod, said stop member being movable from operative to inoperative position, a lever having one end connected to a moving part of the loom 15 and the other end slidably embracing said rod, said lever being adapted to engage said stop member when said stop member is in operative position and move said rod in one direction, resilient means for moving said rod in the other direction, a manually operable lever pivotally mounted on the loom, means connecting said manually operable lever to said stop member for moving said stop member to inoperative position when said manually operable lever is depressed thereby rendering said let-off mechanism inoperative.

6. In a loom, let-off mechanism including a shaft, a ratchet wheel fixed thereto, a pawl carrier loosely mounted on said shaft, a rod slidably mounted on the loom and pivotally connected to said pawl carrier at one end, a stop member pivotally connected to said rod, said stop member being movable from operative to inoperative position, a lever having one end connected to a moving part of the loom and the other end slidably embracing said rod, said lever being adapted to engage said stop member when said stop member is in said operative position and move said rod in one direction, resilient means for moving said rod in the other direction, a manually operable lever pivotally mounted on the loom, a Bowden wire having one end associated with said manually operable lever and the other end associated with said stop member for moving said stop member to inoperative position when said lever is depressed to thereby render said let-off mechanism inoperative.
